CLAIM

The ornamental design for a swimming pool cover, as shown and described.

DESCRIPTION

FIG. 1 is a perspective view of the swimming pool cover shown positioned over a swimming pool, the swimming pool forming no part of the design;

FIG. 2 is a top view of the swimming pool cover;
FIG. 3 is an end elevational view of the right end of the swimming pool cover, the left end being a mirror image thereof;FIG. 4 is a front view of the swimming pool cover; and,
FIG. 5 is a rear view of the swimming pool cover.

The broken line showing the environment in FIG. 1 is for illustrative purposes only and forms no part of the claimed design.

FIG. 1

FIG. 2

FIG. 3

FIG. 4

FIG. 5
